(57) **CLAIM**

The ornamental design for a countercurrent prevention rectal syringe, as shown and described.

DESCRIPTION

FIG. 1 is a perspective view of a countercurrent prevention rectal syringe showing our new design;

FIG. 2 is a front elevational view thereof;

FIG. 3 is a top plan view thereof;

FIG. 4 is a left side elevational view thereof;

FIG. 5 is a rear elevational view thereof;

FIG. 6 is a right side view thereof; and,

FIG. 7 is a bottom plan view thereof.

1 Claim, 7 Drawing Sheets(56)
